UNITED STATES PATENT OFFICE.

STEPHEN J. CLULEE, OF ATTLEBORO, MASSACHUSETTS, ASSIGNOR TO BAY STATE OPTICAL COMPANY, OF ATTLEBORO, MASSACHUSETTS, A CORPORATION OF MAINE.

EYEGLASSES.

1,182,350.

Specification of Letters Patent.

Patented May 9, 1916.

Application filed August 8, 1912. Serial No. 713,953.

To all whom it may concern:

Be it known that I, STEPHEN J. CLULEE, a citizen of the United States, residing at Attleboro, in the county of Bristol and State 5 of Massachusetts, have invented certain new and useful Improvements in Eyeglasses, of which the following is a full, clear, and exact description, such as will enable others skilled in the art to which it appertains to 10 make and use the same.

This invention relates to eye-glasses, and with regard to certain more specific features thereof, to improvements in eye-glass mountings.

15 One of the objects of the present invention is to provide an eye-glass mounting which will be easy to construct and assemble and inexpensive to manufacture.

Another object is to provide an eye-glass 20 mounting which will be simple and practical in its construction and automatic in its adjustment to noses of different shapes.

A further object is to provide a durable 25 and compact eye-glass mounting of the last above-mentioned character which may be manually adjusted in various ways.

Other objects will be in part obvious and in part pointed out hereinafter.

The invention accordingly consists in the 30 features of construction, combinations of elements and arrangement of parts which will be exemplified in the construction hereinafter set forth, and the scope of the application of which will be indicated in the following claims.

In the accompanying drawing, wherein is shown one of various possible embodiments of this invention,—Figure 1 is a rear elevation showing one-half of a complete 40 mounting; Fig. 2 is a top plan view of the part shown in Fig. 1; Fig. 3 is a bottom plan view of a portion of the mounting shown in Figs. 1 and 2; Fig. 4 shows the parts in disconnected position; and Fig. 5 is a detail view, partly in section.

Similar reference characters refer to similar parts throughout the different views of the drawing.

Referring now in detail to the drawing, 50 and more particularly to Fig. 1, a saddle or bridge portion 1 is provided with field pieces 2 at each end thereof, upon which guard arms 3 are mounted to turn. Provided at the extreme ends are clamping lugs

4 adapted to hold lenses 5 securely against 55 supporting shoes or straps 6.

Each field piece comprises a relatively wide flat portion having an upper bearing surface 7 upon which the guard arm turns, and is provided with a vertically disposed 60 cylindrical hole or opening 8. Mounted in this hole is a tubular member 9 having a bearing flange or collar 10 adapted to rest upon the upper surface of the guard arm 3 and hold it in place. This tubular member is 65 split its entire length, as indicated at 12 (Fig. 5), to permit contraction and expansion thereof when springing the member in the support and when adjusting its position, as will be more fully hereinafter explained. The upper part of the slot 70 extending longitudinally of the tubular member 9 is slightly enlarged, as indicated at 13 (Fig. 5) to receive the inner end 14 of a flat spiral spring 15, the opposite end 16 75 of which is hooked about a lug or projection 17 on the inside of the guard arm 3 in such a manner as to urge a guard 18 carried thereby toward the side of the nose as the spring tends to uncoil.

The lower part of the tubular member 9 is threaded on the inside, as clearly shown in Fig. 5, to receive a cylindrical screw 19, the head 20 of which is tapered, as indicated by the surface 21. The inner edge of 85 the tubular member is also tapered or beveled, as indicated at 22, but at a more acute angle, whereby as the screw is tightened, the head will engage the outer end of the beveled surface 22 and flare the same outwardly to firmly hold the tubular member 90 in adjusted position by its frictional contact with the inner wall of the opening 8. It will also be noted that the head 20 of the screw is of a diameter equal to or less than 95 the diameter of the hole 8, thus making it possible, when assembling the parts, to insert the screw in the tubular member before the member is passed through the opening in the field piece, after which the parts may be adjusted to their final position and the screw 100 tightened to hold the parts in their adjusted position.

The tubular member 9 is not only split, as previously stated, entirely along one side, 105 but is also provided, at its upper end, with a small notch 23 diametrically opposite the split 12 to permit the reception of a screw

driver for the purpose of turning the tubular member to adjusted position. It will, of course, be understood that on turning this tubular member the spiral spring 15 carried thereby will become more or less tensioned, according to the direction of rotation.

While the method of use and operation of a device of this character will probably be obvious from the above description, a brief statement thereof is as follows: In mounting the eye-glasses upon the nose, the actuating arms 24 at the front end of the guard arms are grasped between the thumb and finger and moved toward each other to separate the guards 18 at the rear. This movement also tends to increase the tension of the spiral spring 15 positioned about the tubular member 9. On releasing the actuating arms the springs will force the guards toward each other and against the sides of the nose, thus securely holding the glasses in place. As the guards are pivotally mounted at 25 upon the rear ends of the guard arms they will, of course, more easily conform to the peculiar inclination of the nose of the wearer.

If it becomes necessary to increase or decrease the tension of the spring, the adjusting screw 19 on the under side of the field piece is released to relieve the wedging pressure upon the beveled surface 22 of the tubular member 9. A screw driver is then inserted in the upper end of the split 12 and notch 23 and the tubular member rotated the desired amount. It is held in this position until the adjusting screw can again be tightened to hold the parts firmly in adjusted position, as above described.

It is thus seen that this invention provides a simple and practical eye-glass mounting adapted to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:—

1. In finger-piece eyeglasses, in combination, a supporting member having an opening, a guard lever to turn thereon and having a registering opening, a pivot extending

through said openings and having an expansible tubular portion within said first-mentioned opening, and means within said tubular portion to expand the latter for gripping the adjacent walls of said member. 70

2. In finger-piece eyeglasses, in combination, a supporting member having an opening, a guard lever to turn thereon and having a registering opening, a pivot extending through said openings and having an expansible portion within said first-mentioned opening, screw means within said expansible portion to expand the same for gripping the adjacent walls of said supporting member, and a positioning spring for said guard lever coiled about the opposite end of said pivot. 75 80

3. In a device of the class described, in combination, a member provided with an opening, a split tubular member sprung into said opening, and a spring-actuated guard-arm mounted to turn on said first-mentioned member. 85

4. In a device of the class described, in combination, a member provided with an opening, a second member in said opening having a flaring mouth, a screw positioned within said mouth having a tapered portion adapted to engage the same, the taper of said screw being more abrupt than that of said flaring mouth, and a spring-actuated guard-arm mounted to turn on one side of said first-mentioned member. 90 95

5. In a device of the class described, in combination, a member provided with an opening, a split tubular pivot pin sprung into said opening, a spring actuated guard arm adapted to turn on said pivot pin, and a notch in said tubular member opposite the split adapted to receive a holding tool. 100 105

6. In a device of the class described, in combination, a member provided with an opening, a split tubular pivot pin sprung into said opening, a guard-arm adapted to turn on said pivot pin, and a spring adapted to act upon the guard arm and the pivot pin. 110

7. In a device of the class described, in combination, a member provided with an opening, a split pivot pin mounted in said opening, a screw threaded in said pin having a tapered portion adapted to engage and tend to expand the pivot pin, a spring actuated guard arm mounted upon said pivot pin, and means for holding the guard arm in place. 115 120

8. In a device of the class described, in combination, a supporting member having an opening, an expansible pivot pin mounted in said opening, a guard arm adapted to turn on said pivot pin, said pivot pin having a flaring mouth, and a screw positioned within said mouth and having a tapered portion adapted to engage the same, the head of the screw being of a size to pass through said opening. 125 130

9. In a device of the class described, in combination, a saddle having a field piece provided with an opening, a member in said opening having a flaring mouth, a screw positioned within said mouth having a portion tapered at a greater angle than the flare to said mouth, and a spring coil about said pivot pin and having its free end coacting with the guard arm to urge the guard carried thereby toward the side of the nose.

10. In a device of the class described, in combination, a supporting member provided with an opening, a second member rotatably mounted in said opening, a guard arm mounted to turn on said member, a spring interposed between said member and guard arm, and a screw in said member having a head adapted to pass through the opening in the supporting member, said second member having a notch at the end opposite the screw adapted to receive a screw driver for turning the same.

11. In a device of the class described, in combination, a bridge connection, a swinging lever carrying a nose grip, a split tubular member rotatably mounted in one of the two first mentioned parts, a spring sur-

rounding said member and directly connected at one end thereto and at the other end to the other of said first mentioned parts, and means for securing said member in any desired angular adjustment, comprising a wedge adapted to expand said tubular member.

12. In a device of the class described, in combination, a bridge connection, a swinging lever carrying a nose grip, a split tubular member rotatably mounted in an opening in one of the two first mentioned parts, a spring surrounding said member and directly connected at one end thereto and at the other end to the other of said first mentioned parts, and means for securing said member in any desired angular adjustment, comprising a screw threaded into said tubular member having a head adapted to pass through said opening.

In testimony whereof I affix my signature, in presence of two witnesses.

STEPHEN J. CLULEE.
